191,834

KNIFE FOR HARVESTING ASPARAGUS AND THE LIKE

Thomas Yarrows, Box 77 West St., West Hatfield, Mass.

Filed Aug. 16, 1960, Ser. No. 61,783

Term of patent 3½ years

(Cl. D40—1)

FIGURE 1 is a side elevational view of a knife for harvesting asparagus and the like, showing my new design;

FIGURE 2 is a side elevational view thereof on an enlarged scale, with a portion of the handle being broken away for convenience of illustration;

FIGURE 3 is a front perspective view thereof, on a further enlarged scale, a portion of the handle being broken off for convenience of illustration;

FIGURE 4 is front elevational view thereof as shown in FIGURE 2;

FIGURE 5 is a bottom plan view thereof; and

FIGURE 6 is a rear elevational view thereof with parts broken off for convenience of illustration.

I claim:

The ornamental design for a knife for harvesting asparagus and the like, as shown.
